Inventor
John G. Sturgeon

UNITED STATES PATENT OFFICE.

JOHN C. STURGEON, OF ERIE, PENNSYLVANIA.

GAS-OPERATED AUTOMATIC FIREARM.

1,290,850.

Specification of Letters Patent.

Patented Jan. 7, 1919.

Application filed February 5, 1917. Serial No. 146,669.

To all whom it may concern:

Be it known that I, JOHN C. STURGEON, a citizen of the United States, residing at Erie, in the county of Erie and State of Pennsylvania, have invented certain new and useful Improvements in Gas-Operated Automatic Firearms; and I do hereby declare the following to be a full, clear and exact description of the invention, such as will 5 enable others skilled in the art to which it appertains to make and use the same, reference being had to the accompanying drawings, and to the letters of reference marked thereon, forming part of this specification.

10 This invention relates to fire-arms, and particularly to gas-operated automatic firearms wherein a portion of the gases of each discharge operate to unlock, move back the breech-bolt mechanism, operate the cartridge feeding mechanism and compress a 15 spring or springs which operate to close and lock the breech-bolt and actuate the firing pin.

One object of this invention is to construct 20 and assemble the operative mechanism so that all parts of it are easily accessible to the operator, and can, if necessary, be quickly removed from and replaced in the frame of the arm, through the rear end thereof.

25 Another object of this invention is to provide a vertically moving breech-bolt locking mechanism engaged and actuated by a supplemental piston communicating with and operating the bolt-locking mechanism, 30 which piston is first moved back by the gases to unlock the bolt and compress a retracting spring operating thereon, and then moves on in unison with the breech-bolt and locking mechanism, until the mechanism completes its rearward movement, and then 35 when the bolt and its locking mechanism has completed its reverse movement, the supplemental piston is moved forward by the spring so as to operate the locking-lug to effectually lock the bolt in firing position.

Another feature of this invention consists 40 of cartridge-feeding mechanism which positively feeds cartridges to the arm, and a cartridge supply device, preferably rotatable, with means thereon for removably securing cartridges to its periphery, which device can be quickly put in place and deliver the cartridges thereon to the feeding

mechanism, and which can be quickly removed when exhausted and replaced by a 55 full cartridge supply device.

Another feature of this invention consists in the cartridge feeding mechanism, the mechanism for operating the same, and the mechanism for actuating the cartridge supply device intermittently, to supply cartridges to the feeding device.

Another object of this invention is to provide barrel-cooling mechanism consisting substantially of thin corrugated strips of 65 metal, such as copper or aluminum, secured longitudinally to the barrel with a shell secured around the same, and conical disks secured to the outer end of the barrel within said shell, whereby each discharge of the 70 arm operates to produce a strong current of air through the shell over the corrugated strips on the barrel, and thereby cool the same.

Another object of this invention consists 75 substantially in the structure of parts, their co-operation and combination in the arm as hereinafter described.

These and other features of this invention are hereinafter fully set forth and described 80 and illustrated in the accompanying drawings in which:—

Figure 1, is a side view in elevation, of the frame of the arm, the rear portion of the barrel, a portion of the hinged butt, and a 85 side view in elevation of the rear sight of the arm.

Fig 1^a, shows a top or plan view in elevation, of the rear sight of the arm.

Fig. 1^b, shows a transverse section of the 90 barrel and cooling mechanism therefor, on the line A in Fig. 1, looking in the direction of the arrow.

Fig. 2, shows the muzzle portion of the barrel of the arm, partially in elevation and 95 partially in section.

Fig. 2^a, shows a front end view of the muzzle end of the arm.

Fig. 3, shows a longitudinal vertical section, partially in elevation, showing the 100 mechanism of the arm in the frame, and its position when ready to fire.

Fig. 4, is a like longitudinal vertical section, partially in elevation, showing the 105 mechanism of the arm in its position when re-loading.

Fig. 5, is a longitudinal horizontal section of the frame and rear end of the barrel on the plane of the bore of the barrel, with a section of the cartridge supply clip showing 5 a cartridge in position to enter the barrel, and an empty shell being ejected thereby, with some of the parts in elevation.

Fig. 6, is a transverse section of the same 10 on the line E, in Fig. 5, looking in the direction of the arrow.

Fig. 7, is a like transverse section on the line F in Fig. 5, looking in the direction of the arrow.

Fig. 8, is a rear end view of the frame 15 when the butt is turned down, as shown in dotted lines in Fig. 1.

Fig. 9, is a transverse section of the frame on the line B in Fig. 4, looking in the direction of the arrow.

Fig. 10, is a transverse section on the line 20 C in Fig. 3, looking in the direction of the arrow.

Fig. 11, is a horizontal section showing a detail of the cartridge carrying mechanism, 25 and the mechanism for intermittently rotating the cartridge supply disk.

Fig. 12, is a transverse section on the line 30 D in Fig. 3, looking in the direction of the arrow, showing an end view of the cartridge carrying mechanism, and of the side plate on the right hand side of the frame, opened.

In these drawings 1 indicates the frame of the arm, 2 the shoulder butt thereof pivoted at the lower end of the frame on the 35 pintle 2^a, and secured to the end of the frame at the upper part thereof by the transverse pin 1^a, whereby, by the removal of the pin 1^a, the butt may be turned down as indicated by dotted lines in Fig. 1.

To the front end of the frame 1, the barrel 3 is secured by means of an interrupted 40 screw thread 3^a and a screw stud 3^b as shown in Figs. 3, 4 and 5, and 4 indicates the shell of the barrel cooling mechanism secured 45 thereto in any convenient manner.

The sides of the frame 1 are closed by 50 side plates 5 and 5^a, shown in Figs. 1 and 5. The side plate 5 on the right hand side of the plate being hinged thereto by hinges 6 55 at the lower edge thereof, and secured at its upper edge by rotating hooks 7 as clearly shown in Fig. 1; while the side plate 5^a is preferably permanently secured to the left side of the frame.

Extending downwardly from the rear end 60 of the frame there is a hand grip 8 provided with a trigger guard 9 inclosing trigger 10, the construction and operation of which is hereinafter more fully described.

Slidably mounted in the rear end of the frame there is a part 11, preferably secured thereto by means of a transverse key 12, passing through the rear end of the frame. The lower portion of this part 65 11 supports the main spring 13, while

upon the upper portion of this part 11 are mounted the sears 14 and 15; the trigger 10 engaging the arm of the sear 15 as indicated in dotted lines in Fig. 4. Behind the trigger 10 there is a spiral retracting spring 70 16 which operates to retain the trigger in its normal forward position, and behind the sears 14 and 15, are spiral springs 17 and 18 operating respectively upon the sears 14 and 15 as clearly shown in Figs. 3, 4 and 5; the 75 sears 14 and 15 being mounted upon and supported by a pintle 19, shown in dotted lines in Fig. 5, passing through the front end of the upper part of the movable portion 11, whereby, on removal of the key 12, 80 the section 11 with the sear mechanism thereon, and the spring 13, can be speedily removed through the rear end of the frame and re-placed therein when desired.

Mounted in the upper part of the frame, 85 in line with the bore of the barrel 3 is a breech-bolt 20. This breech-bolt passes through the sides 21-22 of the locking-lug frame, and is secured therein by means of a collar 23 thereon, shown in Fig. 3, which 90 collar enters a recess in the portion 21 of the locking-lug frame. The bolt passes on through the frame 22 where it is secured by means of an extension 24, screw-threaded thereto, which completes the rear portion of the breech-bolt; the rear end of this extension being provided with an inward shoulder 25 against which the rear end of the firing-pin spring 26 abuts, as clearly shown in Fig. 3.

The firing-pin 27 passes through the breech-bolt in the usual manner, and has on the rear end thereof a block 28 provided with the usual sear notch 29, and also provided with a forward extension 30, on the 105 lower part thereof, which, when the firing-pin is in its forward position, as shown in Fig. 4, passes under the rear portion of the bolt and retains the sears 14-15 out of contact therewith.

Mounted so as to slide vertically on the bolt, between the sides 21 and 22, of the locking frame, there is a locking lug 31 provided with projections 32 extending into corresponding recesses 33 in the sides and top of 115 the frame when in its upper-most position; but when moved downward to unlock the bolt, the lugs 32 travel backward in unison with the locking-lug frame, in slots 34, in the inner face of the frame.

For operating this locking-lug up and down, there is a bell crank lever 35-36 pivoted at its angle in ears 31^a, on the lower part of the locking-lug 31. The arm 36 of this bell crank lever is pivoted in the side 22 of the locking-lug frame, while the arm 35 thereof extends downwardly and is provided with a slot embracing the central section of a longitudinally moving part 38 mounted in the lower part 39 of the locking 130

frame, and with transverse slots therein operating on the stud-pin 37 secured in said moving part 38.

From the front end of the part 39, a tube 40 extends forwardly through the lower part of the frame 1, and under the barrel 3 into a cylinder 41, under the barrel, the front end of which cylinder communicates by means of passages 42-43, with the bore of the barrel 10 adjacent to the muzzle end thereof, and in the lower part of the passage 43, there is a thumb-screw 43^a, whereby the volume of gas passing through the passage can be adjusted and controlled. Extending from the front 15 end of the part 38, through the tube 40, there is a rod 44 provided with a piston 45 located some distance from the end of the tube 40 when in its normal position relative to the end of said tube, as clearly shown in 20 Fig. 3; and when the gases first enter the front end of the cylinder 41 from the bore of the barrel, they operate to move the piston 45 against the front end of the tube 40; this operates to move the part 38 rearwardly, 25 compressing the spring 46 carried by the rear portion 39 of the locking frame, and at the same time it carries the lower arm 35 of the bell-crank lever 35-36 rearwardly with it, which operates to move the locking lug 31 downward in the locking-lug frame 30 so as to disengage it from the slots 33 in the frame; the further action of the gas against the piston 45 then operates to move the locking frame 21-22, and the parts carried 35 thereby, together with the breech-bolt 20, rearwardly, so as to compress the spring 13 backwardly into the lower portion 11^a of the part 11 at the rear of the frame. This operates to withdraw the bolt and the spent 40 shell from the barrel back to a point where the shell is ejected through an opening 1^b, in the right hand side of the frame, as clearly illustrated in Fig. 4, ready to receive a fresh cartridge to be forced into the barrel 45 by the bolt as the parts are again moved forward by the action of the spring 13; when this forward traverse is completed the spring 46 acting upon the bell crank-lever 35-36, moves the arm 35 thereof forward 50 so as to raise the locking-lug 31 into engagement with the slots 33 of the frame; this movement of the locking-lug 31 just as it is being completed, operates to raise a vertically sliding wedge 47 mounted in the part 55 21 of the locking-frame, as clearly shown in Figs. 3, 4 and 10, which movement of the wedge 47 engages the end of an arm or rod 48, which extends rearwardly to and is connected with the arm 14^a, of the sear 14, and 60 operates to disengage the sear 14 from the sear-notch 29 on the firing-pin 27, which allows the firing-pin to move forward and explode the cartridge.

It is manifest that if the trigger 10 is held 65 backward so as to retain the sear 15 out of

engagement with the sear-notch on the firing-pin, the arm will be automatically fired by the upward movement of the wedge 47 as hereinbefore described; but when the locking-lug 31 is moved downward, the wedge 47 is also moved downward so that the end of the rod 48 will pass over it, as illustrated in Fig. 4; the rod being retained in position by means of a guide 48^a on the side of the part 22 of the locking frame. 75

For feeding cartridges to the firing-bolt, I provide an arm 49 which is mounted upon a sleeve 50, which in turn is mounted upon the tube 40; the sleeve 50 being provided with a cam slot 51 in which a stud 52, secured in the tube 40 operates to oscillate the sleeve 50 as the tube 40 moves forward and backward therethrough; the sleeve 50 being prevented from longitudinal movement by an arm 53 engaging a slot 54 in the end of 85 said sleeve, as clearly illustrated in Figs. 3, 4, 11 and 12.

On the sleeve 50 there is a lug 55 which, when the sleeve 50 is rotated by the forward movement of the tube 40, by engaging the cartridge carrier 49 operates to move the cartridge carrier downward into the position shown in Fig. 12, ready to receive a fresh cartridge; this movement occurring substantially mid-way of the forward traverse of the bolt 20. Meanwhile, as the forward traverse to the tube 40 and the bolt 20 is being completed, an arm 56, preferably removably secured to the tube 40 by means of a laterally projecting lug 56^a, thereon, and having a lateral stud 57 thereon, is moved forward by the traverse of the tube 40 until the stud 57 engages the arm 59 of the oscillating lever 58-59, which causes the arm 58 of said lever to engage a stud 60 on the end of the arm 75 which carries a dog 61 operating on ratchet teeth 62, on a rotatable cartridge supply device 63 (see Figs. 3, 4, 7 and 11) the mechanism whereof is herein-after more fully described, and operates to 105 rotate said cartridge supply device forward one notch and thereby delivers a fresh cartridge upon the end 49^a of the cartridge carrier 49, this action of the parts being repeated at each reciprocal movement of the 110 bolt 20.

For moving the cartridge carrier 49 to carry the cartridge in front of the bolt, as the bolt completes its rearward traverse, I preferably provide, in the cartridge carrier 120 49, a spiral spring 64, the outer end of this spring 64 being engaged by an arm 65 on the sleeve 50, so that during the rearward traverse of the bolt, the cartridge carrier 49 is moved upward carrying the cartridge therewith; and when the bolt is about mid-way of its backward traverse, the cartridge is being held by the carrier 49 against the side of the bolt, and the spring 64 is compressed under more or less tension, so that when the 130

bolt passes back to its rearmost point of traverse, as illustrated in Figs. 4 and 5, the expansion of the spring 64 operates to force the cartridge carrier 49 carrying the cartridge therewith, against the spent shell, so as to push the spent shell outward through the slot 1^b in the arm, and leave the fresh cartridge in front of the end of the bolt ready to be forced into the barrel, as illustrated in Fig. 5; this action being automatically repeated so long as the cartridge supply device has any cartridges remaining thereon to be supplied to the arm.

For cocking the arm there is provided a slot 67 in the side plate 5, as shown in Figs. 1 and 5. Covering this slot there is an arm 68 on the rear end of which there is a knob 59 for operating the same. On the front end of the arm 68 there is an inwardly projecting lug 70 which operates in the slot 67 and extends inwardly from the plate far enough to engage the lug 71, shown in dotted lines at the front end of the slot, and in full lines at the rear end of the slot, in Fig. 5. This lug extends outwardly from the part 38, mounted in the lower part 39 of the locking frame 21 and 22, and operates, when the knob 69 is grasped and pulled backward along the side of the frame, to first operate the unlocking apparatus, and then move the entire locking frame and contents back to the position shown in Fig. 4; the mechanism being moved forward by the spring 13, carries the knob 59 and arm 68 back to their normal position as shown in Figs. 1 and 5, leaving the arm cocked and ready to fire; then, by pulling back the trigger 10, the arm is fired and will automatically operate, so long as the supply of cartridges is fed thereto.

For supporting the cartridge supply mechanism, I secure to the left side of the frame, at the front end of the cartridge supply slot 72, a laterally projecting arm 73. (See Fig. 5). The inner face of this arm is provided with a slot in which an arm 75 is pivoted, having on the end thereof the stud 60, which passes under and is engaged by the arm 59 of the oscillating lever 58—59. Under the arm 75 there is a spring 75^a, which operates to raise the arm 75. In this arm 75 is mounted a sliding part 76, actuated by a spring 76^a, upon the outer end of which part there is a dog 61 adapted to engage ratchet teeth 62 in a rotatable cartridge supply device 63 and rotate it.

At the rear end of the cartridge inlet slot 72 I provide another arm 74 extending laterally from the left side of the frame. This arm is pivoted on a pintle 77 and is provided with a spring 78 whereby it may be swung backward as indicated in dotted lines in Fig. 5.

On the inner faces of the outer ends of

the arm 73—74 are lugs or bosses 79—80, 65 adapted to enter central openings 81 in the disks 82—83 forming the ends of the removable cartridge supply device, whereby the cartridge supply device, when in place between the arm 73—74 will rotate freely 70 upon the inwardly projecting lugs or bosses 79—80. Between the peripheries of these disks 82 I secure the peripheral shell 84 of this cartridge supply device. This peripheral shell is provided at its forward end with 75 raised ratchet teeth 62 stamped into the metal so as to project outwardly therefrom, as illustrated in Fig. 7; and in the rear half of this shell 84 I stamp out therefrom small clips 85—86—87 which are so bent 80 outwardly as to clasp and firmly hold cartridges, as illustrated in Fig. 5. The ends of this cartridge holder 82—83, and the peripheral part thereof 84, I make of thin sheet metal, and connect the peripheral 85 shell with the ends thereof by means of small lugs 84^a on the edges of the shell, which pass through openings in the edges of the ends 82—83 thereof. (See Fig. 5).

As hereinbefore described, this cartridge 90 holder, when in place, is adapted to be intermittently rotated forward one tooth at each forward and backward movement of the bolt 20, and is prevented from backward movement by a spring-dog 61^a mounted in 95 the frame, which engages the teeth 62 as shown in Fig. 7, so that each movement thereof will supply a cartridge to the cartridge carrier 49, as illustrated in Fig. 6, until the entire number of cartridges occupying the periphery of the cartridge carrier has been exhausted; then, by swinging back the arm 74, a newly filled cartridge supply device can be placed therein.

For preventing the excessive heating of 105 the barrel 3, I secure longitudinal corrugated radial strips 88 of thin copper or aluminum, preferably secured to the barrel by being inserted in dove-tailed grooves 89 in the periphery thereof, as illustrated in Fig. 1^b, and to the end of the barrel I secure a collar 90 from which arms 91 extend forwardly; and upon these arms 91 I secure a series of conical deflecting disks 92, as illustrated in Fig. 2, which conical disks 110 operate, as the gases leave the muzzle of the barrel, to deflect a portion thereof outward, toward the inside of the shell 4, which encloses the radial strips 88, and the disks 92, 115 whereby the outward blast of the gases passing from the barrel, operates to produce a strong draft of air over the corrugated radial strips 88, carrying therewith a large per cent. of the heat generated in the barrel 3. 120

The arrangement and operation of the mechanism of this arm has been hereinbefore so fully described that it is believed 125

that further description of the operation thereof is unnecessary.

I have thus shown and described my improved automatic fire-arm so as to enable others skilled in the art to which this invention appertains, to construct and utilize the same. I do not, however, confine myself to the exact construction, form and arrangement of the parts thereof, as many of these can be modified and varied without departing from the spirit of my invention.

Therefore what I claim as new and desire to secure by Letters Patent is:—

1. In a gun, a frame, a barrel secured thereto, a cylinder under the barrel communicating therewith, a reciprocating breech-bolt, a locking-lug frame secured thereto, a reciprocating locking-lug mounted therein adapted to engage lugs on the gun-frame, means in said locking-lug frame for moving the locking-lug, a rod communicating therewith having a piston within said cylinder, and a spring in said locking-lug frame operating in opposition to said piston.

2. In a gun, a frame, a barrel secured thereto, a cylinder under the barrel communicating therewith, a reciprocating breech-bolt, a firing-pin mounted therein, a locking-lug frame secured thereto, a reciprocating locking-lug therein adapted to engage and be disengaged from lugs on the gun-frame, a lever engaging and operating said locking-lug, a rod connected to said lever and a piston in said cylinder operating said rod in one direction, and a spring in said locking mechanism operating to move said rod and lever in the opposite direction.

3. In a gun, a frame, a barrel secured thereto, a cylinder under the barrel communicating with the bore thereof, a breech-bolt, a locking-lug frame secured to said bolt, a vertically movable locking-lug therein adapted to engage the gun-frame, a bell-crank lever pivoted in said locking-lug frame and engaging said locking-lug, a sliding member in said locking-lug frame, a spring in said frame engaging said sliding member, a rod extending from the front of said sliding member into said cylinder, and a piston on the end of said rod within said cylinder.

4. In a gun, a frame, a barrel secured thereto, a non-rotatable reciprocating breech-bolt mounted in said frame, an extractor hook carried thereby, a spring-actuated firing-pin mounted in the breech-bolt, a locking-lug-frame removably secured to the breech-bolt, a locking-lug operating within the locking-lug frame, a gas-operated means for moving the locking-lug frame and breech-bolt rearwardly, and a spiral retracting spring engaging the rear of the locking-

lug frame to move it and the breech-bolt 65 forwardly.

5. In a gun, a frame, a barrel secured thereto, a non-rotatable breech-bolt reciprocable therein, an extractor on the breech-bolt, a locking-lug frame removably secured 70 to the breech-bolt, gas-operated means operating on the locking-lug frame to move it and the breech-bolt rearwardly, a spiral retracting spring engaging the rear of the locking-lug-frame to move it and the breech-bolt 75 forwardly, a vertically movable locking-lug slidably mounted in the locking-lug-frame, lugs on the locking-lug engageable with lugs on the inside of the gun-frame, and means carried by the locking-lug-frame for operating the locking-lug to 80 engage it with and disengage it from the gun-frame.

6. In a gun, a frame, a reciprocating breech-bolt mounted therein, a locking-lug 85 frame secured to said breech-bolt, a spring behind the rear end of said frame to move it forward, a tubular rod secured to the opposite end of said frame and extending forward under the barrel, a sleeve mounted on said tubular rod, means for preventing longitudinal movement of said sleeve on said tube, a cam-slot in said sleeve, a stud on said tubular rod operating in the cam-slot in said sleeve as said rod reciprocates to 90 rotate the sleeve on said rod, a cartridge carrying arm mounted and rotating on said sleeve, a lug on said sleeve adapted to engage said arm and move it in one direction, and a spring mounted in the cartridge carrying arm and a lug on said sleeve engaging said spring to move said arm in the opposite direction.

7. In a gun, a frame, a barrel secured thereto, a cylinder under the barrel, a 105 breech-bolt, a locking-lug frame secured to said bolt, a spring at the rear thereof, a tubular rod extending from the locking-lug frame into said cylinder, a sleeve mounted on said tube, means for preventing the longitudinal movement of said sleeve, an oscillating cartridge carrying arm removably mounted on and adapted to rotate on said sleeve, a cam-slot in said sleeve, a stud in said tube operating in said cam-slot to rotate the sleeve on said tube, a lug on said sleeve adapted to engage said arm and move it in one direction, a spring mounted in said arm and a lug on said sleeve engaging said spring to move said arm in the opposite direction.

8. In a gun, a frame having a cartridge receiving opening therein, a cartridge carrying arm in said opening, means intermittently operating the same, laterally projecting arms on said frame, a cylindrical cartridge supply device removably mounted between said arms, means for removably

securing cartridges to the periphery of said cartridge supply device, ratchet teeth on the periphery of said cartridge supply device, and dog mechanism adapted to engage 5 said ratchet teeth, and means for intermittently operating said dog mechanism.

9. In a gun, a frame having a cartridge receiving opening at one side thereof, a cartridge carrying arm in said opening, 10 laterally projecting arms at each end of said opening, one of which is pivotally secured to the frame, a dog mechanism mounted in the other arm, and means for intermittently operating it.

10. In a gun, a frame having a cartridge 15 receiving opening therein, a laterally projecting arm on the frame at the front end of said opening, a dog mechanism mounted therein adapted to be engaged and intermittently operated by reciprocating mechanism in the frame, and an arm projecting laterally from the rear end of said cartridge receiving opening pivotally connected with the frame, and a spring acting thereon to maintain it in its normal position. 20 25

In testimony whereof I affix my signature.

JOHN C. STURGEON.
